UNITED STATES PATENT OFFICE.

JOHN T. AUSTIN, OF HARTFORD, CONNECTICUT, ASSIGNOR TO THE AUSTIN ORGAN COMPANY, OF HARTFORD, CONNECTICUT, A CORPORATION OF CONNECTICUT.

ORGAN STOP ACTION.

Application filed January 12, 1926. Serial No. 80,807.

The present invention relates to organ stop actions and has particular reference to means for recording desired stop combinations for future use.

5 Heretofore, in stop actions of this sort, it has been necessary, in order to prepare the recording mechanism so that the stops of a desired combination could be simultaneously operated at some subsequent time, to manually and singly operate the stop keys, pedals or other operating members associated with the desired stops. When an artist was composing or improvising on the organ and happened to play a certain combination of 15 stops which developed splendid tones colorful to the impromptu composition being played, and he desired to record that combination for future use or repetition, it was necessary for him to interrupt the playing 20 and manually and individually press a number of stop keys or pedals.

The aim of the present invention is to provide an improved stop action by means of which an artist may prepare, for future 25 use or repetition and without interfering with the rendition of the number being played or composed, any desired stop combination which he may play. My improved arrangement is such that to record a given 30 combination of stops which have been played, it is merely necessary, before that combination is disturbed, for the artist to operate a single member, such as a thumb piston, and when it is desired to again bring 35 on the same combination, all the artist has to do is to press the thumb piston again.

A further aim of the invention resides in the improved arrangement which is characterized by its simplicity and compactness 40 in construction and by its smoothness and effectiveness in operation.

Other objects will be in part obvious and in part pointed out more in detail herein-after.

45 In the accompanying drawings, I have shown one embodiment which the present invention may take, but it is to be understood that this disclosure is by way of exemplification only and my invention is susceptible of various modifications and 50 changes. For instance, in the drawings, I have shown an electro-mechanical control, but it is obvious that the various elements may be operated pneumatically, electrically or mechanically, either in whole or in part.

Various other arrangements are possible within the spirit of the appended claims.

In said drawings:

Figure 1 is a view showing, more or less diagrammatically, the recording mechanism 60 of the present invention, the cams or actuators thereof being in unlocked condition;

Fig. 2 is a view similar to Fig. 1, but illustrates certain of the cams locked in operative position; 65

Fig. 3 is a top plan view of my improved recording trace mechanism and also shows traces such as are disclosed in certain of my earlier patents as, for instance, Patent No. 1,078,079 and Patent No. 1,456,612; 70

Fig. 4 is a view taken substantially on line 4—4 of Fig. 2;

Fig. 5 is an enlarged fragmentary view in top plan showing the actuators and locking bar in unlocked position; 75

Fig. 6 is a view similar to Fig. 5, but shows the parts in locked position;

Fig. 7 is a view taken substantially on line 7—7 of Fig. 6; and

Fig. 8 is a fragmentary view showing a 80 portion of a trace which is old in the art.

In order that the improvements of the present invention may be more clearly understood, I have shown the same in connection with trace mechanisms such as are disclosed in my said Patent No. 1,078,079. All of the trace mechanisms illustrated may be operated in accordance with the disclosure of my Patent No. 1,456,612, but it will be understood, of course, that my improvements 85 may be used in other combinations than here illustrated and may be variously operated.

Referring first to the trace mechanisms constructed in accordance with my earlier patents, *a*, *a* designate traces having pivoted 90 actuators or cams *b* provided with *T* heads adapted to be adjusted above or below the respective traces. Only a few of these actuators are illustrated in the drawings for purposes of illustration. Each actuator is provided with a pair of bosses which co-operate with the head of the stud *c* on which the next preceding actuator is pivoted in such manner that each actuator is held or frictionally locked in each of its positions of adjustment; that is to say, in stop canceling position and stop drawing position. The traces pass through skeleton rollers *d*, each of which is adapted to be rocked from 95 "off" to "on" position or vice versa by the in- 100

- dividual or associated operating member, such as a stop key or pedal, these operating members not being shown in the drawings as they are well-known in the art. The traces are carried for longitudinal movement on a suitable pan *e*. Each trace carries an armature *f* operated by a respective magnet *g*. Each of these magnets *g* has an associated thumb piston or pedal. These pistons 10 are not shown with the exception of the one for the trace in which is embodied the improvements of the present invention. Common to all of the pistons and the magnets *g* is a solenoid *h* which, when energized, moves 15 an impeller *i* towards the right, referring to Figs. 1, 2 and 3. The spring *k* returns the impeller when the solenoid *h* is de-energized. The operation of the construction so far described will be clearly understood from 20 my foregoing patents, it being here sufficient to say that when it is desired to record any selected combination on one of the traces *a*, the piston associated with that trace is pushed in, thereby energizing the respective 25 magnet *g* which lifts the armature *f* associated with that magnet into the path of movement of the impeller *i*. Also, when the piston is pushed in, the solenoid *h* is energized so as to advance the impeller *i* and that trace *a* the armature *f* of which has 30 been raised. Then, while the piston is held in to maintain the parts in advanced position, the selected rollers are individually rocked so as to set the desired actuators in 35 operative or stop drawing position. Thereafter, the piston is drawn out or released, with the result that the trace is returned by a respective spring *m* to inoperative position. 40 With traces constructed as just described, it is necessary, in order to record any given combination of stops, to hold the trace on which the combination is to be recorded in advanced position and manually and individually operate the keys or pedals of the 45 respective rollers associated with the stops which it is desired to record; which means that, in the event it is desired to record a selected combination of stops during the rendition of a composition, it is necessary to 50 interrupt the playing. It is noted that the actuators are always locked in their operative or inoperative position so that, when the trace is advanced, the actuators will 55 turn the rollers with which they come into engagement. The traces *a* may constitute what are called "generals"; that is, they may be effective in all divisions of the organ, or they may represent traces which are effective 60 on only certain divisions of the organ. In accordance with the present invention, I provide a trace mechanism with actuators or cams normally loosely mounted on the trace so that, when the artist operates the piston, pedal, tablet, or other operating member of that trace to advance the latter, the cams respectively associated with the stops which have been drawn will be rocked into operative position by their engagement with the actuated rollers of those stops, and 70 all of the cams, after certain of them have been rocked to operative position as just described, are locked against movement relative to the trace by a bar. Then the trace with the cams locked thereon is returned to 75 inoperative position and when the artist desires to again call into play the combination of stops recorded, it is merely necessary for him to push in the piston associated with my improved trace, thereby advancing the latter 80 and causing the cams to rock those rollers, which are not in desired positions, simultaneously into the desired positions and without the necessity of manipulating the stop keys or pedals. The selected combination of stops may be recorded after each time the selected combination of stops has 85 been played, or the combination may be varied at will and the modified combination recorded without interrupting the playing 90 of the composition. 95 Referring more specifically to the drawings, 10 designates the trace of my improved mechanism. This trace is mounted for reciprocation in the trace pan *e* and carries the cams or actuators 11 for rocking the rollers *d*. The rearwardly extending portion of each cam overlaps the forward end of the next preceding cam and is provided with two projections or bosses 12 which, when the cams are flexed by the locking bar, are adapted to receive similarly shaped heads 13 of the studs 14 on which the actuators are pivoted. The cams are loosely mounted on their respective pivots so that, when they are not held in locked positions by the locking bar, they normally assume the position shown in Fig. 1; that is, with their lower ends projecting below the trace. In the present instance, each cam is offset at its intermediate portion, as at 15, so that normally the actuators spring apart laterally to assume the position shown in Fig. 5. 20 designates a locking bar mounted for limited floating movement on the trace 10. In the present illustrative disclosure, this bar is supported on the trace by brackets or staples 21, the staples being preferably spaced in accordance with the distance between the pivotal points of the cams. The staples are so positioned as to bridge the cams at their overlapping points. The arrangement is such that the staples prevent the actuators from being unhooked from the trace 10 during the unlocking movement of the bar, and 110 the staples limit the downward movement of the actuators. 115 The locking bar 20 is provided with lateral projections or bosses 22 which are spaced in accordance with the spacing of the actuators 120 125 130

11. When the locking bar is in the unlocked position shown in Fig. 1, the bosses 22 are out of engagement with the bosses on the cams 11 so that all of the cams or actuators 5 are unlocked and are, therefore, free to be rocked upon an advancing movement of the trace into stop drawing position by the respective stop rollers which are in "on" position. When the bar is in the locking position 10 shown in Fig. 2, the bosses thereon engage the opposed bosses of the actuators, thereby springing these actuators so that the heads of the studs 14 engage in the recesses provided by the bosses 12, which 15 means that the actuators are locked against rocking movement.

The trace 10 may be moved into and out of operative position in a manner similar to that in which the other traces *a* are advanced 20 and, to this end, the trace 10 may have an armature 30 controlled by a magnet 31 which, in turn, is controlled by a thumb piston 32.

The numeral 35 designates an intermittently rotated release wheel adapted to cooperate with the rear end of the locking bar, as hereinafter described more in detail. 25 This release wheel is longer than it is wide so as to provide a pair of arms 36, so to speak. The release wheel is fixed to a stub shaft 37 journalled in a stationary bracket 38 and has, extending from its face, ratchet lugs 39. Fixed on the shaft 37 is a bushing 40 between which and the bracket is interposed a spring 41 for preventing the wheel 35 from over-running. The rotation of the release wheel is controlled by a pawl 42 pivotally mounted on the rearmost stud 14 of the main trace and has a hooked portion 43 adapted to engage the lugs 39. With this arrangement, on each forward movement of the trace 10, the wheel 35 will be rotated 90° or a quarter of a revolution.

The operation of my improved recording mechanism is briefly as follows: Assuming 45 that the artist is improvising and has drawn, more or less at random, a combination of stops which is so well suited to the movement being played that it is desired to repeat the same movement as the improvisation progresses, it is merely necessary for the artist, without interrupting the rendition of the composition, to push in on the thumb piston 32, thereby advancing the trace 10 with all of the actuators in the unlocked position shown in Fig. 1. When this trace is thus advanced, those rollers associated with the stops which have been drawn, and which, for convenience, are designated by the letter *d'*, will rock the respective actuators 11' upwardly; that is, into the stop drawing position shown in Fig. 2. As the forward movement of the trace 10 proceeds, the locking bar is held against longitudinal movement owing to the engagement 60 of the forward end of the bar against

the front wall of the trace pan, with the result that the bosses 22 on the locking bar will be brought into engagement with the respective bosses on the actuators, thereby camming or springing these actuators laterally so that the heads 13 of the studs engage in the registering recesses of the bosses 12. Thus, the locking bar will lock or hold those actuators 11' which have been rocked into stop drawing position and will hold the remaining actuators in their lowermost or stop cancelling position. Furthermore, upon the forward movement of the trace 10, the wheel 35 is rotated a quarter of a revolution from the position shown in Fig. 1 to that shown 70 in Fig. 2. The desired combination now having been recorded on the trace 10, the piston 32 is released or drawn out, whereupon the spring 25 will withdraw the trace to the inoperative position shown by dotted lines Fig. 2 and, upon this return movement of the trace, the locking bar moves therewith, because the interengagement of the bosses on the bar and the actuators produces sufficient friction to hold the parts in locked position upon return movement of the trace. 80 After the trace has been moved to return position, the stops of the combination which have just been recorded may be used in various other stop combinations without disturbing in any way the setting of the recording mechanism.

As the rendition of the impromptu or composition progresses, it may be desired to draw various other stop combinations in 100 order to produce the proper tone colors for various other movements, thereby variously changing the stops of the recorded combination, which means that certain of the recorded stops will be cancelled and other stops not of record will be drawn. Having arrived at a point where it is desired to re-draw the recorded stop combination, the piston 32 is again actuated and the recording trace mechanism as a whole will be brought forward. During this forward movement, the cams or actuators 11', which are locked in stop drawing position, will operate the respective rollers *b'* to re-draw the recorded stops which were cancelled in preceding movements, and the remaining actuators, which are in stop cancelling position, will operate the respective rollers of these unrecorded stops which have been drawn to cancel the same, thus rendering the original combination effective to again cause the selected stops to render the same tone colors as the particular movement for which they were originally drawn. At the completion of the forward movement of the trace 10, the wheel 35 is rotated by the pawl 42 a quarter of a turn to the position shown in Fig. 1. When the circuit is again opened, the trace 10 is retracted by the spring 25 to normal position, and, since 115 120 125 130

the wheel 35 holds the locking bar against endwise movement, the bosses of the actuators will ride from under the projections on the locking bar with the result that those 5 actuators which have been in raised or stop drawing position will drop of their own weight into normal or stop cancelling position, and the various elements will assume the unlocked position shown in Figs. 1 and 10 5. The force of the spring 25 is sufficient to break the friction holding the parts in locked position, so as to effect the unlocking thereof when the circuit is opened by releasing the thumb piston. After the 15 particular movement has been re-played, the same stop combination may again be recorded by simply pressing the piston 32, or the recording mechanism may be held in readiness for recording a stop combination 20 of different tone colors which are especially suited to other movements as they may develop. It will be seen from the foregoing that each time the trace mechanism is returned to inoperative position after it had 25 been advanced to operate the stop rollers, the trace mechanism is unlocked and is in readiness for recording a different stop combination; or the same movement, such as a theme, may be intermittently repeated any 30 number of times by recording the stop combination during the playing or at the conclusion of each repetition thereof; that is to say, at any time before the stops, which have been drawn on and which it is desired 35 to record, are disturbed depending upon the instant at which the artist's thumb or finger is near the piston 32 while playing.

Preferably, the recording trace mechanism is effective in all divisions of the organ; 40 that is to say, every stop on the organ console will have a corresponding actuator on the recording mechanism. It is obvious, therefore, that a stop combination may include couplers combined with the speaking 45 stops and various other combinations may be had. The thumb piston for operating the recording mechanism may be conveniently located on the lower name board of the organ console and, in case a pedal is 50 used separately or with the thumb piston for operating the trace 10, it will be conveniently located on the toe board.

In the drawings, I have shown but one of my improved recording trace mechanisms, 55 but, obviously, the organ may have any desired number of such mechanisms.

As many changes could be made in the above construction and many apparently 60 widely different embodiments of this invention could be made without departing from the scope thereof, it is intended that all matter contained in the above description or shown in the accompanying drawing shall be interpreted as illustrative and not in 65 a limiting sense.

It is also to be understood that the language used in the following claims is intended to cover all of the generic and specific features of the invention herein described and all statements of the scope of 70 the invention which, as a matter of language, might be said to fall therebetween.

I claim as my invention:

1. In combination, a plurality of elements 75 each constituting a part of a respective stop action and each having an "on" position and an "off" position, and means for simultaneously recording the positions of said elements at will.

2. In combination, a plurality of elements 80 each constituting a part of a respective stop action and each having an "on" position and an "off" position, and recording mechanism including a plurality of actuators respectively associated with said elements and arranged to be simultaneously set by bringing the actuators into engagement with said elements to record the positions of the latter.

3. In combination, a plurality of elements 90 each constituting a part of a respective stop action and each having an "on" position and an "off" position, and trace mechanism having a plurality of actuators respectively associated with said elements, said trace mechanism being bodily movable and said actuators being free to be simultaneously adjusted by said elements to record the positions thereof when said mechanism is moved. 95

4. In combination, a plurality of elements 100 each constituting a part of a respective stop action and each having an "on" position and an "off" position, and a bodily movable trace provided with a plurality of normally loose actuators each having a stop drawing 105 position and a stop cancelling position, said actuators being simultaneously set by engaging the same with said elements upon movement of said trace.

5. In combination, a plurality of elements 110 each constituting a part of a respective stop action and each having an "on" position and an "off" position, and recording mechanism provided with a plurality of actuators arranged to be simultaneously set to record the 115 positions of said elements by bringing said actuators into engagement with the adjusted elements, said mechanism including means for automatically locking said actuators in adjusted positions. 120

6. In combination, a plurality of elements 125 each constituting a part of a respective stop action and each having an "on" position and an "off" position, a movable trace, a plurality of actuators loosely mounted on said trace and respectively associated with said elements, said actuators being moved to set position by engaging the same with the set elements upon movement of said trace, and means for automatically locking and unlock- 130

ing said actuators upon movement of said trace.

7. In combination, a plurality of elements each constituting a part of a respective stop action and each having an "on" position and an "off" position, and recording trace mechanism having a plurality of actuators respectively associated with said elements, said actuators being arranged to be set by 10 engaging the same with the adjusted elements upon one movement of said trace mechanism and the set actuators being arranged to bring said elements into the desired combination of positions up on a subsequent movement of said trace mechanism.

8. In combination, a plurality of elements each constituting a part of a respective stop action and each having an "on" position and an "off" position, a longitudinally movable 20 trace provided with a plurality of actuators respectively associated with said elements, and a locking bar for automatically locking said actuators in recording positions upon movement of said trace.

25 9. In combination, a plurality of elements each constituting a part of a respective stop action and each having an "on" position and an "off" position, a longitudinally movable trace, a plurality of actuators loosely mounted thereon and adapted to be simultaneously adjusted by the set elements upon a given longitudinal movement of said trace, and a locking bar for automatically locking all of 30 said actuators in adjusted position and holding the same in that position until after the trace mechanism has been employed to again bring the elements to the desired combination of positions.

40 10. In combination, a plurality of elements each constituting a part of a respective stop action and each having an "on" position and an "off" position, a longitudinally movable trace having a plurality of loosely mounted actuators thereon adapted to be simultaneously set by engaging the same with the set elements upon one movement of the trace in a given direction, and means for simultaneously and automatically locking said actuators in set position when said trace is 45 so moved, said locking means holding said actuators in locked position upon the next movement of said trace in the same direction and then releasing said actuators.

55 11. In combination, a plurality of elements each constituting a part of a respective stop action and each having an "on" position and an "off" position, a longitudinally movable trace having a plurality of actuators thereon, a locking bar for locking said 60 actuators in set position, said actuators upon one advance movement of said trace being simultaneously adjusted by the elements in their set positions, and said locking bar being held against movement on such movement of said trace to result in locking said

actuators in adjusted position, said locking bar being movable with said trace on its return movement and on its next advance movement, and means for preventing said locking bar from moving with said trace on its next return movement whereby said actuators are unlocked.

75 12. In combination, a plurality of elements each constituting a part of a respective stop action and each having an "on" position and an "off" position, a longitudinally movable trace, a plurality of actuators loosely mounted thereon, a locking bar associated with said trace and arranged on one return movement of said trace to move 80 therewith and on the next return movement of said trace to remain stationary, and means controlled by the movement of said trace for controlling the movement of said bar.

85 13. In combination, a plurality of elements each constituting a part of a respective stop action and each having an "on" position and an "off" position, a longitudinally movable trace, a plurality of actuators thereon, a locking bar for locking said actuators in set position, said locking bar being held against movement on one advance movement of said trace, said locking bar being movable with said trace on the return movement of 90 the latter and on the next advance movement, and a member operated by the movement of said trace for holding said locking bar against movement with said trace upon the next return movement of the latter.

95 14. In combination, a plurality of elements each constituting a part of a respective stop action and each having an "on" position and an "off" position, a longitudinally movable trace, a plurality of loosely pivoted actuators thereon each having a pair of bosses, a locking bar having projections adapted to engage the respective bosses on said actuators and thereby hold the actuators in set positions, said locking bar being 100 held against movement upon one advance movement of said trace to result in locking of said actuators, said bar being movable with said trace on the next return movement and the next advance movement thereof, 110 whereby said actuators are held in set positions to actuate the said elements, and a release wheel controlled by the movement of said trace for holding said locking bar against return movement after the operative movement of said trace.

115 15. In combination, a plurality of elements each constituting a part of a respective stop action and each having an "on" position and an "off" position, a longitudinally movable trace, a plurality of pivoted actuators thereon each having a pair of bosses, a locking bar having a plurality of projections adapted to engage said bosses and thereby flex said actuators to lock the same in said 120 130

positions, a release wheel arranged upon one return stroke of the trace to permit the locking bar to move therewith and on the next return stroke of said trace to hold said bar against movement with said trace, and a pawl carried by said trace and cooperating with said wheel for turning the latter upon advance movements of said trace.

16. In combination, a plurality of ele-

ments each constituting a part of a respective stop action and each having an "on" position and an "off" position, a longitudinally movable trace provided with a plurality of actuators respectively associated with said elements, and means for automatically locking said actuators in recording positions upon movement of said trace. 10 15

JOHN T. AUSTIN.
